UNITED STATES PATENT OFFICE.

JACOB B. GOLDSMITH, OF ROCKPORT, MASSACHUSETTS.

IMPROVEMENT IN HOLDBACKS.

Specification forming part of Letters Patent No. **158,370**, dated January 5, 1875; application filed July 16, 1874.

To all whom it may concern:

Be it known that I, JACOB B. GOLDSMITH, of Rockport, in the county of Essex and State of Massachusetts, have invented an Improved Holdback-Iron for Carriage-Shafts; and I do hereby declare that the following, taken in connection with the drawings which accompany and form part of this specification, is a description of my invention sufficient to enable those skilled in the art to practice it.

The invention relates to holdback irons or hooks for carriage-shafts; and consists in the special construction hereinafter particularly described.

The drawing represents a shaft-iron embodying the invention.

Figures 1 and 2 show the construction in side and sectional elevation. Fig. 3 shows the construction in plan.

a denotes the main plate or bar, having at its front end a hole, *b*, through which passes a screw that enters the shaft, and at its rear end a vertical screw-shank, *c*, that passes through the shaft, and is permanently secured to the shaft by a suitable nut on the shank under the shaft. The bar is slotted, as seen at *d*, and in said slot is a strong horizontal spring, *e*, supported at its opposite ends on shoulders *f*. Over the screw-shank is an arm, *g*, that extends up from the bar, and then bends over into horizontal position, as seen in the drawing. The bar *a* is made with vertical ears *h*, in which are supported gudgeon-pins *i*, extending from a lever, *k*, having right-

angular arms *l* *m*. The arm *l* has, at its top, an eye, *n*, that swings over the point of the stationary arm *g*. The lever *k* is held in normal position by the spring *e* and the pressure against it of a block-rubber spring, *o*. When the strap is to be inserted the arm *l* is thrown down to the shaft. Then, by drawing the strap against the arm *m*, it is left inclosed between the arm *g* and the arm *l*. The spring holds the lever with sufficient firmness in position to keep the holdback-strap from slipping out, but, if the traces break, the holdback-strap will bear against the lever-arm *l*, freeing the horse from the carriage. Extending back from the stationary arm *g* is a brace, *p*, having a hole, *q*, through which a screw passes into the shaft. By the brace *p*, the screws passing through the holes *p* *q*, and the screw-threaded shank-piece secured by the nut, the holdback-iron is securely fastened in position, and is also made very enduring in its own construction.

I claim—

The holdback-iron formed of the bar *a*, having the screw-shank *c*, arm *g*, brace *p*, and having pivoted to the bar *a* the lever *k*, provided with an eye, *n*, in one of its arms, all combined substantially as shown and described.

J. B. GOLDSMITH.
